RAILWAY SIGNALING APPARATUS

Robert M. Gilson, Pittsburgh, Pa., assignor to
The Union Switch & Signal Company, Swiss-
vale, Pa., a corporation of Pennsylvania

Application May 10, 1935, Serial No. 20,796
Renewed February 5, 1936

30 Claims. (Cl. 246—34)

My invention relates to railway signaling apparatus, and more particularly to apparatus of the type involving track circuits.

An object of my invention is to provide novel and improved apparatus for insuring the release of a track relay when vehicles having wheels which do not make dependable electrical contact with the rails, or which are completely insulated therefrom by non-conducting tread material, enter the section of track with which the relay is associated.

I will describe various forms of apparatus embodying my invention, and will then point out the novel features thereof in claims.

15. The railway signaling apparatus set forth in my present application is somewhat similar to that set forth in the two copending applications of Howard A. Thompson, Serial No. 617,137, filed on June 14, 1932, for Apparatus for shunting of track circuits, and Serial No. 629,030, filed on August 16, 1932, for Apparatus for decreasing rail contact resistance, and the said copending applications contain claims which cover broadly certain features of the invention described in my 20 present application.

In the accompanying drawing, Figure 1 shows, in elevation, a rail vehicle provided with equipment cooperative with the track circuits embodying my invention; while Figs. 2, 3, and 4 show different forms of track circuits each embodying my invention and each cooperative with the vehicle-carried equipment shown in Fig. 1. These figures also shew a part of the vehicle-carried equipment shown in Fig. 1.

35. Similar reference characters refer to similar parts in each of the several views.

Referring first to Fig. 1 of the drawing, the reference character A designates a rail vehicle the wheels of which do not make electrical contact with the rails, because of being equipped with pneumatic tires or any other suitable insulating tread material. Mounted upon car A is a direct current generator G, driven by a motor M. One terminal of generator G makes contact with one rail of the track by means of a brush 3, and the other terminal of generator G makes contact with the remaining rail by means of a brush 4 through a current limiting resistor Z. Connected across resistor Z is an indicator L, of any suitable type, such as a lamp, for indicating that the current from generator G is being passed into the rails of the track.

The apparatus so far described provides a method of superimposing a direct current from a source aboard a rail vehicle, upon the rails of

the track, and for checking that the superimposed current is actually being conducted into the rails. The manner in which such current becomes effective to shunt the track circuit will be apparent from a description of the remaining figures 5 of the drawing.

Referring to Fig. 2, the reference characters 1 and 2 designate the traffic rails of a railway track which are provided with insulated rail joints 5 to form a track section E—F. The track section 10 E—F is provided with a track circuit, the essential elements of which comprise the traffic rails 1 and 2, a source of current connected across the traffic rails at one end of the section and a track relay energized by energy taken from the traffic 15 rails at the opposite end of the section.

Considering the source of current for the track circuit of section E—F, the secondary winding 20 of a track transformer T has one terminal connected with the rail 1 by conductor 15; and its other terminal connected with rail 2 through a condenser C, windings 7 and 6 in series of a reactor R to be referred to later, and a conductor 14. The primary winding of the transformer T is connected with any convenient source of periodic current, such as an alternating current generator, not shown in the drawing. It follows that the transformer T constitutes a source of periodic current from which current is constantly supplied to the traffic rails of the section E—F. 25

The reactor R is preferably of the type commonly known to the art as a "three-legged" reactor. The windings 6 and 7 are mounted on the two outer legs, respectively, and are identical and additive as to magnetomotive force and, consequently, substantially no flux created thereby 30 will pass through the center leg. The capacity value of condenser C and reactance value of the windings 6 and 7 are such that they are normally tuned to series resonance for the particular frequency of the track circuit current. This results in a limiting impedance between the transformer T and the track having a value of approximately the ohmic resistance of the reactor coils 6 and 7.

Mounted on the center leg of reactor R is a winding 8, also connected across the track rails 1 and 2, adapted to receive direct current when a vehicle such as A occupies the section. A reactance coil 13 is included in the circuit of winding 8 to prevent any appreciable amount of alternating current from flowing through the winding 8, while the condenser C in the track feed circuit prevents direct current supplied to the winding 8 from passing through the windings 6 and 7. At the relay end of the 35 40 45 50 55

track circuit a relay transformer T_1 is interposed between the track relay feed leads 16 and 17 and the usual alternating current track relay D.

When a vehicle such as A occupies section E-F 5 the direct current supplied to the rails by the generator G through brushes 3 and 4 passes through reactance 13 and the winding 8 on the middle leg of reactor R in series therewith. This current magnetically saturates the iron core of the 10 reactor R thereby reducing the impedance of the reactor and destroying the resonance between condenser C and the windings 6 and 7. This results in greatly increasing the total limiting impedance between the transformer T and the 15 track, thereby reducing the amount of alternating current energy supplied from the secondary winding of transformer T to the track rails.

Simultaneously, a portion of the direct current applied to the rails 1 and 2 flows through the 20 primary winding of the relay transformer T_1 , saturating its core, thereby reducing its impedance and increasing the load on the track circuit at the relay end to further reduce the amount of current supplied to the relay D. As a consequence, the track relay D will release its front contact to provide a suitable danger signal for following traffic.

A still greater reduction in energy fed to the track relay can be brought about by shunting 30 the primary winding of the relay transformer T_1 with a condenser. For example, by closing switch S at the relay end of the circuit a condenser C₁ is connected in multiple with the primary winding of transformer T_1 . The value of this condenser is so chosen as to produce multiple resonance with the wattless component of the transformer magnetizing current. This reduces the normal load at the relay end of the track circuit to some extent, but greatly increases the load at 35 this point when a vehicle enters the section and reduces the reactance of the primary winding of transformer T_1 by feeding direct current through it.

In Fig. 3 I have shown substantially the same 45 apparatus as shown in Fig. 2, but have shown a modification of the apparatus at the feed end of the track circuit. In this case the secondary winding of transformer T is connected to rail 1 by conductor 15 and to rail 2 over a path including a current limiting resistor X and conductor 14. Connected across conductors 14 and 15 is a series circuit including winding 8 of the reactor R and reactance 13; while another path across conductors 14 and 15 includes windings 6 and 7 of reactor R and the condenser C. In this form of the invention the reactance of windings 6 and 7 of reactor R and the capacity of condenser C are so chosen that normally with the section E-F unoccupied and no direct current flowing through winding 8 of reactor R, the circuit is out of resonance and therefore shunts very little of the current being supplied to the rails by the secondary of transformer T.

When a vehicle such as A enters the section, the 65 direct current supplied by it to the track rails 1 and 2 and to winding 8 saturates the iron core of the reactor R, thereby reducing its reactance and providing series resonance between windings 6 and 7 and the condenser C. In this way, the 70 impedance across the track feed leads 14 and 15 becomes very low when the track is occupied, causing a large voltage drop across resistance X. This results in a marked reduction in energy supplied to the track relay, insuring its release.

75 The arrangement of Fig. 3 may be modified to

operate in a slightly different manner, by connecting a condenser across the track feed leads. For example, by closing switch S₁ the auxiliary condenser C₂ becomes connected across the track circuit feed leads 14 and 15. With this arrangement the condenser C is merely employed to block the flow of direct current through the alternating current coils 6 and 7 of the reactor. The value of condenser C₂ is such that with the track unoccupied multiple resonance normally exists between condenser C₂ and the predominating reactance of the circuit including condenser C and the windings 6 and 7 of the reactor R. This results in very little load being placed across the track circuit feed leads 14 and 15 with the 15 section unoccupied. When, however, the section becomes occupied by a vehicle which applies direct current to the rails 1 and 2 and winding 8, the multiple resonance formerly existing is destroyed, thereby greatly lowering the impedance 20 across leads 14 and 15 and causing a large reduction in the amount of energy being fed to the track rails and to the track relay.

In Fig. 4 I have shown a variation of Fig. 3 involving the employment of a reactor R¹ at the 25 relay end of the track circuit, the use of which provides a more sensitive arrangement than those formerly described. In this form of the invention, the windings 6¹ and 7¹ of reactor R¹ and condenser C¹ are connected in series across the 30 track relay feed leads 16 and 17, in multiple with the primary winding of the relay transformer T_1 ; while the winding 8¹ and reactance 13¹ are connected in series across the relay feed leads 16 and 17. These connections correspond to those at 35 the feed end of the section, but do not include a condenser corresponding to condenser C₂. The reactor R¹ normally functions in the same manner as R with switch S₁ open, and therefore normally shunts very little current from the primary 40 winding of transformer T_1 .

When, however, a vehicle such as A enters the section, the direct current fed to winding 8¹ saturates the core of reactor R¹, thereby reducing its reactance and providing series resonance between its windings 6¹, 7¹, and the condenser C¹. This results in a great reduction in the impedance across the relay feed leads 16 and 17, causing the major portion of any alternating current which has not been shunted through the windings 50 6 and 7 of reactor R at the feed end of the section to be shunted from the primary winding of the relay transformer T_1 .

Although I have herein shown and described 55 only a few forms of apparatus embodying my invention, it is understood that various changes and modifications may be made therein within the scope of the appended claims without departing from the spirit and scope of my invention.

Having thus described my invention, what I claim is:

1. In combination with a section of railway track, a source of periodic current, means for connecting said source across the traffic rails of 65 the section comprising a tuned circuit including a condenser in series with a first winding of a reactor having a magnetizable core, a track relay receiving current from the rails of said section, vehicle-carried means for supplying direct current to the traffic rails of said section for detuning said tuned circuit to increase the effective impedance thereof, and a second winding on said reactor arranged to receive direct current from said vehicle to control the flux in the core of 70 75

the reactor and thereby aid the release of said track relay.

2. In combination with a section of railway track, a source of periodic current, means for connecting said source across the traffic rails of the section including a first winding of a reactor having a magnetizable core, a track relay receiving current from the rails of said section, means for supplying direct current to the traffic rails of the section when and only when occupied by a vehicle, and a second winding on said reactor receiving direct current from the rails of said section and varying the permeability of the core of said reactor to control the periodic current supplied to the traffic rails.

3. In combination with a section of railway track, a source of periodic current, means for connecting said source across the traffic rails of the section including a first winding of a reactor having a magnetizable core, a track relay receiving current from the rails of said section, a second winding on said reactor, and means for supplying direct current to said second winding when and only when the section is occupied to control the flux in the core of the reactor.

4. In combination with a section of railway track, a source of periodic current, means for connecting said source across the traffic rails of the section comprising a tuned circuit including a condenser in series with a first winding of a reactor having a magnetizable core, a second winding mounted on the core of said reactor, means including a vehicle-carried source of direct current for energizing said second winding when a vehicle occupies said section to create a steady magnetic flux for detuning said tuned circuit and increasing the effective impedance thereof so that the voltage of the periodic current supplied across the traffic rails is decreased or increased respectively in accordance with the presence or absence of a train in said section, and an electroresponsive device receiving current from the rails of said section effectively influenced by the periodic current.

45 5. In combination with a section of railway track, a source of periodic current, a reactor having a magnetizable core provided with a center and two outside legs, means for connecting said source across the traffic rails of the section comprising a tuned circuit including a condenser in series with a first and a second winding mounted on the outside legs respectively and arranged in such a manner that magnetomotive forces created thereby are additive, a third winding mounted on the center leg, vehicle-carried means including a source of direct current, circuit connections for energizing said third winding from said source of direct current responsive to a train entering said section for detuning said tuned circuit and increasing the effective impedance thereof so that the voltage of the periodic current supplied to the traffic rails is decreased or increased respectively in accordance with the presence or absence of a train in said section, and an electroresponsive device receiving current from the rails of said section effectively influenced by the periodic current.

6. In combination with a section of railway track, a source of periodic current, a reactor having a magnetizable core provided with a center and two outside legs, means for connecting said source across the traffic rails in a circuit including a first and a second winding mounted on the outside legs respectively and arranged in such a manner that magnetomotive forces created

thereby are additive, means included in the circuit effective to tune the same to series resonance for the particular frequency of the periodic current, a third winding mounted on the center leg of the reactor, vehicle-carried means for supplying unidirectional current to said third winding when the section is occupied to control the permeability of the core of said reactor and in so doing detune the circuit to govern the periodic current supplied to said traffic rails, and a traffic governing electroresponsive device receiving periodic current from the traffic rails.

7. In combination with a section of railway track, a source of periodic current, a reactor having a magnetizable core provided with a center and two outside legs, means for connecting said source across the traffic rails at one end of the section including a first and a second winding mounted on the outside legs respectively and arranged in such a manner that magnetomotive forces created thereby are additive, a third winding mounted on the center leg, vehicle-carried means including a source of direct current with circuit connections therefrom for energizing said third winding when and only when the section is occupied to create a steady magnetic flux for determining the reactance of said first and second windings and thereby control the periodic current, and a traffic governing electroresponsive device receiving periodic current from the rails of said section.

8. In combination with a section of railway track, a source of periodic current, a reactor having a magnetizable core provided with an auxiliary and two main magnetizable legs, means for connecting said source across the traffic rails including a first and a second winding mounted on the two main legs respectively, means for connecting a third winding mounted on the auxiliary leg of the reactor across the rails of the section, means including a source of direct current connected across the traffic rails when and only when the section is occupied by a vehicle to energize the third winding by direct current to create a magnetic flux in the core of the reactor for determining the reactance of said first and second windings and thereby control the periodic current, and an electroresponsive device effectively controlled by periodic current received from the rails of said section.

9. In combination with a section of railway track, a source of periodic current, means for connecting said source across the rails of said section including a first winding of a reactor having a magnetizable core, operating means receiving current from the rails of said section, means connected across the traffic rails by a vehicle occupying the section for supplying unidirectional current to the rails of said section when and only when said section is occupied, and a circuit including a second winding of said reactor also connected across the traffic rails effectively influenced by the unidirectional current for varying the permeability of the core of said reactor to control the periodic current supplied to said operating means.

10. In combination with a section of railway track, a source of periodic current, means for connecting said source across the traffic rails at one end of the section including a first winding of a reactor having a magnetizable core, means controlled by periodic current received from the rails of said section, vehicle-carried means for supplying the traffic rails with unidirectional current when and only when said sec-

tion is occupied by the vehicle, and means connected across the traffic rails at said one end of the section including a second winding of said reactor energized by said unidirectional current and varying the permeability of the core of said reactor to control the periodic current supplied to the traffic rails.

11. In combination with a section of railway track, a track circuit including a source of periodic current connected with the respective rails of the section, a saturation type of reactor for said section having a plurality of windings one of which is included in said circuit and another winding of which is connected across the rails of the section, a condenser for tuning the first-mentioned winding of said reactor to series resonance, a rail vehicle having a source of direct current thereon, means for conducting current from said source of direct current over the rails of said section through the second winding of said reactor to saturate the core of said reactor so as to detune said tuned winding and thereby change the impedance of said track circuit, and an electro-responsive device effectively controlled by the energy received over the rails of said section.

12. In combination, a section of railway track, a track relay, a track circuit for supplying energy to said track relay including a source of periodic current and the rails of the section, a reactor having a first winding connected in said circuit at a point between said periodic current source and one rail of the section, means included in said circuit for tuning the circuit to series resonance for the particular frequency of the periodic current from said source, a second winding on said reactor connected across the rails of the section, a rail vehicle having a source of direct current thereon, and means for conducting current from said direct current source to the rails of said section and through the second winding of said reactor to detune said circuit and increase its impedance whereby the track circuit energy flowing to said track relay is decreased sufficiently to effect its release.

13. In combination, a section of railway track, a source of periodic track circuit current connected across the rails of said section, a saturation type of reactor having one winding connected between said source and one rail of said section and having a second winding connected across the rails of said section, means included in circuit with said one winding normally reducing the impedance of the path between said source and the rails to substantially the ohmic resistance of the path, vehicle carried means for supplying the second winding of said reactor with direct current when the section is occupied to saturate said reactor and thereby increase the impedance of the path, and electroresponsive means controlled by current supplied over the traffic rails of said section.

14. In combination, a section of railway track, a source of periodic current supplying energy to a track relay for the section over a track circuit including the rails thereof, a first and second winding of a saturation type reactor and a condenser included in the circuit and tuned to series resonance at the frequency of the current from said source, and vehicle carried means supplying energy to a third winding of said reactor saturating the core thereof and destroying the resonance of the track circuit to restrict the supply of energy being fed to the track relay when the section is occupied.

15. In combination, a section of railway track,

a source of periodic current supplying energy to a track relay for the section over the rails thereof, a path for shunting current from said relay including two windings of a saturation type reactor and a condenser tuned to resonance at the particular frequency of said source of periodic current only when a third winding of said reactor is energized, and means including a vehicle carried source of energy for energizing the third winding of said reactor when the section is occupied.

16. In combination, a section of railway track, a source of periodic current supplying energy to a track relay for the section over the rails thereof, a circuit for shunting current from said relay including two windings of a saturation type reactor and a condenser connected in multiple across the rails of the section and normally tuned to multiple resonance at the frequency of the periodic current, a third winding on said reactor, and means including a vehicle carried source of current for energizing said third winding to saturate said reactor and thereby detune said circuit.

17. In combination with a railway track section, a source of periodic current track circuit energy for said section connected across the rails thereof, a track relay for said section receiving energy from the rails thereof, a reactor of the saturation type for said section having a first winding also connected across the rails of said section, a condenser connected in parallel with such winding and being of such a capacity that multiple resonance normally exists between it and the predominating reactance of such reactor winding so that the reactor winding and condenser normally place very little load across said periodic current source, a second winding on said reactor connected across the rails of said section, a rail vehicle having a source of direct current thereon, and means for conducting current from said direct current source to the rails of said section to energize said second winding and thereby saturate said reactor to destroy the multiple resonance condition and decrease the impedance of the first winding of said reactor so that it shunts sufficient current from the track relay to effect its release.

18. In combination with a railway track section, a source of periodic current track circuit energy for said section connected across the rails thereof, a track relay receiving current from the rails of said section, a reactor of the saturation type for said section having a first winding also connected across the rails of said section, means included in circuit with such winding for normally maintaining its impedance very high so that its presence has very little effect on the current being supplied over the rails, a second winding on said reactor, a rail vehicle having a source of direct current thereon, and means for conducting current from said vehicle-carried source to said second winding, thereby saturating the reactor and destroying the effect of said first means so that the impedance of the first winding becomes very low when the section is occupied and accordingly reduces the current being fed to the rails of said section.

19. In combination with a section of railway track, a source of periodic current, means for connecting said source across the traffic rails of the section in multiple with a first winding of a reactor having a magnetizable core, a traffic governing relay, means adapted to receive periodic current from the traffic rails for energiz- 75

- ing said relay, a first winding of a second reactor connected in multiple with said means, vehicle-carried means adapted to feed direct current to the traffic rails of the section, and 5 a second winding on each of said reactors arranged to receive current from a vehicle occupying the section to govern the flux in the cores of their respective reactors, to control the supply of energy being fed to said track relay.
- 10 20. In combination with a section of railway track, a source of periodic current for said section supplying energy over the rails of said section to a track relay for said section, a reactor of the saturation type for said section having 15 two windings connected in multiple with conductors over which energy is supplied to said track relay, a reactance included in circuit with one of said windings substantially blocking the flow of alternating current therethrough, a condenser in 20 circuit with the other of said windings blocking the flow of direct current therethrough, a rail vehicle having a source of direct current thereon, and means for conducting current from said direct current source to the rails of said section 25 to energize the one of said windings to decrease the impedance of the other winding and thereby shunt sufficient energy from the track relay to effect its release.
21. In combination with a section of railway 30 track, a source of periodic current for the section connected across the rails thereof at one end of the section, a relay transformer having its primary winding connected across the rails of the section at the other end thereof and having 35 its secondary winding included in circuit with a track relay for the section, a condenser connected in multiple with the primary winding of said relay transformer and having a capacity of a value which produces multiple resonance 40 with the wattless component of the relay transformer magnetizing circuit and so reduces the normal load at the relay end of the section, a rail vehicle having a source of direct current thereon, and means for conducting current from 45 said source to the rails of said track to saturate the relay transformer magnetizing circuit and thereby destroy its normal resonant condition so as to greatly increase the load at the relay end of the circuit to effect release of the track 50 relay.
22. In combination with a section of railway track, a source of periodic current, a saturable reactor having a pair of windings and a magnetizable core, means including one of said windings for connecting said source across the traffic rails of the section, a track relay receiving current from the rails of said section, and means effective when and only when the section becomes occupied for supplying a saturating current to 55 the other of said windings for controlling the flux in the core of said reactor to thereby control the current received by said track relay.
23. In combination with a section of railway track, a source of periodic current, means including a saturable reactor for connecting said source with the rails of said section, a track relay receiving current from the rails of said section, and means effective when and only when the section becomes occupied for supplying a saturating current to 60 said reactor for controlling the effective impedance thereof to thereby control the current received by said track relay.
24. In combination with a section of railway 65 track, a source of periodic current, means including a saturable reactor for connecting said source with the rails of said section, a track relay receiving current from the rails of said section, and means effective when and only when the section becomes occupied for supplying a saturating current to 70 said reactor for controlling the effective impedance thereof to thereby control the current received by said track relay.
25. In combination with a section of railway track, a source of periodic current, means including a reactor for connecting said source with the rails of said section, a track relay receiving current from the rails of said section, and means effective when and only when said section becomes occupied for supplying an additional current to said reactor for controlling the effective impedance thereof to thereby control the current received by said track relay.
26. In combination with a section of railway track, a source of periodic current, a tuned circuit including a reactor for connecting said source with the rails of said section, a track relay receiving current from the rails of said section, and means effective when and only when said section becomes occupied for supplying an additional current to said reactor to alter the flux condition thereof, thereby altering the tuning of said reactor circuit to control the current received by said track relay.
27. In combination with a section of railway track, a source of periodic current connected with the rails of said section, a track relay receiving current from the rails of said section, a saturable reactor connected with said rails between the rails and said relay, and means effective when and only when said section becomes occupied for supplying a saturating current to said reactor for controlling the effective impedance thereof to thereby control the current received by said track relay.
28. In combination with a section of railway track, a source of periodic current connected with the rails of said section, a track relay connected across the rails of said section, a reactor connected in parallel with said relay, and means effective when and only when said section becomes occupied for supplying a saturating current to said reactor for controlling the effective impedance thereof to thereby control the current received by said track relay.
29. In combination with a section of railway track, a source of periodic current connected with the rails of said section, a track relay connected across the rails of said section, a reactor connected in parallel with said relay, and train carried means effective when and only when said section becomes occupied for supplying a saturating current to said reactor for controlling the effective impedance thereof to thereby control the current received by said track relay.
30. In combination with a section of railway track, a track circuit for said section comprising a source of periodic current and a track relay each connected across the rails of the section, a saturable reactor also connected across said rails, and means effective when and only when said section becomes occupied for supplying a saturating current to said reactor for controlling the effective impedance thereof to thereby control the current received by said track relay.
